UNITED STATES PATENT OFFICE.

ARNOLD AUGUST EGLI, OF KLEIN GUEMMENEN, SWITZERLAND, ASSIGNOR, BY MESNE ASSIGNMENTS, TO CHOCOLAT TOBLER HOLDING CO., AKTIENGESELLSCHAFT, OF SCHAFFHAUSEN, SWITZERLAND.

LINE-BY-LINE TYPEWRITING MACHINE.

Application filed October 18, 1924, Serial No. 744,381, and in Germany October 25, 1923.

This invention relates to line printing typewriting machines or the like and consists more particularly in this, that only for each printing operation the vibrating roller or 5 the like of the inking apparatus is brought in contact for a uniform, preferably regulable period of time with the ink roller in the ink trough, the latter roller being preferably turned after each printing operation through 10 an equal portion of its periphery, while the ink distributing device is held in constant motion. According to the present invention the arrangement is such that the motion of the vibrating roller for causing it to contact 15 with the roller in the ink trough and the rotary motion of the latter roller are capable of being initiated and preferably automatically stopped for each printing operation. The initiation of the motion of the vibrating 20 roller and of the roller in the ink trough is preferably effected by a stop member, while the motion is stopped automatically after one revolution of a corresponding wheel or a corresponding disc. For this purpose for 25 instance a rocking lever may be provided, which is held in its operative position by a cam disc or the like, cause to rotate on being actuated, although the device for initiating the motion returns to its position of rest. 30 Machines of the kind in which the present invention preferably may be used are shown in the prior applications Ser. No. 628,514 and Ser. No. 469,045.

In the accompanying drawing a constructional example of the invention is shown,

Fig. 1 being a diagrammatic side elevation of a device according to the invention,

Fig. 2 a front elevation and

Fig. 3 a plan view of Fig. 1.

40 In the drawing 1 is a cord pulley, on the shaft 2 of which a toothed wheel 3 is mounted, which keeps the toothed wheels 4, 5 and 6 (Fig. 1) in constant rotation. The toothed wheels, 4, 5 and 6 are fixed to corresponding distributing rollers, between which other distributing rollers rotate, which distribute the ink. 7 is a lever, which rocks about a pivotal point 8. The lever 7 is adapted to move the member 9 and to cause thereby the part 34 45 on the member 9 to engage a corresponding part 35 on the toothed wheel 3, when a bar 10 moving in the direction indicated by the arrow strikes against a member 11 on the lever 7. The bar 10 is mounted on a rod 25 which

is connected to an arm 31 linked at 30. The 55 arm 31 carries on its other end the printing roll 33. The lower end of the rod 25 has a crank connection with a toothed wheel 26 which meshes with a wheel 27. When the operator initiates the rotation of the wheel 27—by means of a motor or by hand—the wheel 26 rotates, the rod 25 swings the arm 31 and presses the printing roll 33 on the type carriers 29 which are situated on the table 28 behind the inking apparatus. By the further 60 rotation of the wheel 26 the printing roll is automatically brought back. These operations and means are more particularly described and shown in the said prior application Serial No. 628,514. 70

When the rod 25 is moved down, the bar 10 strikes against the member 11 and the movable member 9 of the coupling, which is adapted to move in the direction indicated by the arrow *a* is fixed to the toothed wheel 12, so that, on the part 34 engaging the part 33, the toothed wheel 12 will turn at the same speed of revolution as the toothed wheel 3. The toothed wheel 12 meshes with a toothed wheel 13, which is mounted on the same shaft 80 as a toothed wheel 14. The latter meshes with the toothed wheel 15 and the toothed wheel 15 with the toothed wheel 16. The toothed wheel 16 which is mounted on the same shaft as the roller in the ink trough, thus turns the 85 roller when the part 34 on the member 9 is in engagement with the coupling part 34 on the toothed wheel 3. On the lever 7 is a pin 17 and on the toothed wheel 13 is an annular rib 18, in which there is a notch 19 (Figs. 2 90 and 3). When the toothed wheel 13 is in its position of rest, the pin 17 engages in the notch in the annular rib and is raised out of the notch on the toothed wheel 13 commencing to rotate. By this arrangement the lever 95 7 is held in its engaged position, although the bar 10 has already moved back again, until the toothed wheel 13 has made a complete revolution. The pin 17 thereupon returns into the notch in the annular rib 18 100 under the action of a spring, 36, and thereby allows the lever 7 and the member 9 of the coupling together with the toothed wheel 12 to return to the position of rest.

Two cam discs 20 and 21 are mounted coaxially with the toothed wheel 13, to which they may be adjustably fixed by means of screws 22. A pin 23_a on a lever 23 rests on

both cam discs, which may be adjusted relatively to one another in a known manner for regulating the operative period of the cams. On the other arm of the lever 23 rests the vibrating roller 24, which is adapted to be moved by the cams 20, 21 into contact with the roller in the ink trough rotated by the toothed wheel 16, each time the latter roller has been turned through a portion of a revolution. By means of this arrangement the top inking roller may be given a perfectly uniform fresh coating of ink after each printing operation with the result that the vibrating roller is not vibrated continuously so as continuously to supply fresh ink to the inking apparatus. In addition to this the roller in the ink trough is caused always to supply the same amount of ink to the vibrating roller. These points are of particular importance in the case of typewriting machines, which print line for line, so that the separate lines may all receive the same quantity of ink. The bar 10, in the drawings connected to the rod 25, may be of course connected to another means of the printing machine which is synchronously moved with the printing device.

I claim:—

1. In a printing machine of the character described, an ink trough, an ink distributing device, a constant drive for keeping the said distributing device in continuous motion, a vibrating ink supplying device supplying ink from the said trough to the said distributing device, a printing device, adapted to be thrown on by the operator for each printing operation for printing a line, and to be thrown off automatically after each printing operation of a line, and intermittent driving means for putting the said vibrating device in motion for a uniform period of time, only for each said irregularly occurring printing operation for the purpose of supplying for each printing operation an equal quantity of ink from the ink trough to the distributing device.
2. In a printing machine according to claim 1, means for regulating the said period of time.
3. In a printing machine according to claim 1, the said vibrating ink supplying device consisting in a roller.
4. In a printing machine according to claim 1, a roller in the said trough cooperating with the said supplying device, and means for rotating the said trough roller for each printing operation an equal part of its periphery.
5. In a printing machine according to claim 1, a roller in the said trough cooperating with the said supplying device, and means for rotating the said trough roller for each printing operation an equal part of its periphery, and the said intermittent drive being adapted to put the said vibrating device in

motion and the said trough roller in rotation.

6. In a printing machine according to claim 1, the said means for putting the said vibrating ink supplying device in motion comprising means for initiating and automatically stopping the movement of the said vibrating device.

7. In a printing machine according to claim 1, a roller in the said trough cooperating with the said supplying device, and means for rotating the said trough roller for each printing operation an equal part of its periphery and the said means for putting the said vibrating device in motion comprising means for initiating and automatically stopping the motions of the said vibrating device and trough roller.

8. In a printing machine according to claim 1, the said intermittent driving means comprising a rotatable member, another member adapted to be moved in connection with the printing device and to initiate the motion of the rotatable member, and means for automatically stopping the motion of the said rotatable member.

9. In a printing machine according to claim 1, a roller in the said trough cooperating with the said supplying device, and the said intermittent drive being adapted to put the said vibrating device in motion and to rotate the said trough roller for each printing operation an equal part of its periphery and the said intermittent drive comprising, a rotatable member, first means for initiating the motion of the said member for each printing operation of the printing device, second means for keeping the said member in motion, and third means for automatically stopping the said member.

10. In a printing machine according to claim 1, a roller in the said trough cooperating with the said supplying device, and means for rotating the said trough roller for each printing operation an equal part of its periphery, the said rotating means comprising a rotatable member, first means for initiating the motion of the said member for each printing operation of the printing device, second means for keeping the said member in motion, and third means for automatically stopping the said member.

11. In a printing machine according to claim 1, a roller in the said trough cooperating with the said supplying device, the said intermittent drive being adapted to put the said vibrating device in motion and the said trough roller in rotation and the said intermittent drive comprising a rotatable member, first means for initiating the motion of the said member for each printing operation of the printing device, second means for keeping the said member in motion, and third means for automatically stopping the said member, each time after one revolution.

12. In a printing machine according to

claim 1, a roller in the said trough cooperating with the said supplying device, and means for rotating the said trough roller for each printing operation an equal part of its periphery, the said rotating means comprising a rotatable member, first means for initiating the motion of the said member for each printing operation of the printing device, second means for keeping the said member in motion, and third means for automatically stopping the said member, each time after one revolution.

13. In a printing machine according to claim 1, a roller in the said trough cooperating with the said supplying device, and means for rotating the said trough roller for each printing operation an equal part of its periphery, the said intermittent drive being adapted for firstly rotating the said trough roller an equal part of its periphery and for then putting, for a uniform period of time, the said vibrating roller in motion.

14. In a printing machine according to claim 1, the said means for initiating and automatically stopping the motions of the said vibrating device and trough roller comprising a rotatable member, another member adapted to be moved in connection with the printing device, a rockable lever adapted to be rocked by the said other member to couple the said rotatable member with the constant drive and to be kept in its rocked position until the said motion of the vibration device is finished.

15. In a printing machine according to claim 1 a pair of coaxially mounted cam disks, adapted to be adjusted relatively to one another by means of a screw and to regulate the said period of time.

16. In a printing machine according to claim 1 the said means for initiating and automatically stopping the movement of the

said vibrating device, comprising a rotatable member, a notch on said member, a rockable lever adapted to cooperate with said member and to engage in its unrocked position the said notch, a device adapted to be moved to and fro corresponding to the movement of the printing device and to rock the said lever out of the engagement with the said notch, further means adapted to return the said lever into its normal position each time the said notch meets with the said lever, and a drive for rotating the said member adapted to be put in motion by the rocking movement of the said lever out of the engagement with the said notch and to be stopped on the return of the said lever into its normal position.

17. In a printing machine according to claim 1 the said means for initiating and automatically stopping the movement of the said vibrating device comprising a rotatable member, a notch on said member, a rockable lever adapted to cooperate with said member and to engage in its unrocked position the said notch, a device adapted to be moved to and fro corresponding to the movement of the printing device and to rock the said lever out of the engagement with the said notch, further means adapted to return the said lever into its normal position each time the said notch meets with the said lever, and coupling means for coupling the said member with the constant drive, the said coupling means being adapted to be moved into its coupling position by the rocking movement of the said lever out of the engagement with the notch and to be returned to its normal position on the return of the said lever into its unrocked position.

In testimony whereof I have affixed my signature.

ARNOLD AUGUST EGLI.
